(57) **CLAIM**

The ornamental design for an ear cup for a headset, as shown and described.

DESCRIPTION

FIG. 1 is a front perspective view, showing the new design for an ear cup for a headset;

FIG. 2 is a front view thereof;

FIG. 3 is a rear view thereof;

FIG. 4 is a right side view thereof;

FIG. 5 is a left side view thereof;

FIG. 6 is a top perspective view thereof; and,

FIG. 7 is a bottom perspective view thereof.

The broken line showing forms no part of the claimed design, and the shading is provided to illustrate contour only and is not an indication of texture, gloss, etc.
